UNITED STATES PATENT OFFICE

JOHN BROMLEY, OF CLOSTER, NEW JERSEY

BASEBALL GLOVE

Application filed April 5, 1928. Serial No. 267,499.

My invention relates to improvements in game- or sport-gloves or mitts, and especially those used in ball games. The nature and advantages of the invention will be sufficiently understood from the present showing and explanation of its adaptation to a baseball fielder's glove.

The principal object is to provide or incorporate in the glove or mitts a sweat guard 10 consisting substantially of a sheet of suitable moisture-proof material, usually rubber, cut approximately to the shape or outline of the glove and inserted at the palm side thereof, usually between the outer 15 leather and the lining, to prevent perspiration from the user's hand permeating the outer leather.

The guard preferably serves as a pad for all or a part of the player's hand, or cooperates with other padding material to protect the hand from the force of the ball impact.

Desirably also the guard has a central palm formation or ball socket adapted to enable the player to more certainly receive and 25 securely hold the ball; or, as otherwise stated, to provide a palm formation similar to that of a thoroughly "broken in" glove, but of a permanent character on account of a definite concave formation in the palm portion of the guard.

The characteristics and advantages of the invention are further sufficiently explained in connection with the following detail description of the accompanying drawing, 35 which shows one representative embodiment.

After considering this example, skilled persons will understand that many variations may be made without departing from the principles disclosed, and I contemplate the 40 employment of any structures that are properly within the scope of the appended claims.

Fig. 1 is a plan view (that is, a view of the front or palm side) of a game glove embodying the invention in one form, with some 45 parts broken away or in section.

Fig. 2 is a section at 2—2, Fig. 1.

Fig. 3 is a plan view of one suitable form of guard.

Fig. 4 is a sectional detail at 4—4, Fig. 3. 50 While the invention may be embodied in

hand apparel of different types, such, for example, as a catcher's mitt, it is here shown as adapted to a glove of the type known to baseball players as a "fielder's glove." This includes the front or palm 1 of suitable sheet 55 material, usually leather, and the back 2, also of sheet material, such as leather or canvas. The front and back sheets are cut and sewed to provide finger portions 3 and a thumb portion 4, as usual, the glove structure proper being of any known or suitable type except for special features of adaptation for the present purposes, as presently noted. The front or palm structure also includes a lining 5 of suitable sheet material, 60 usually soft leather, secured to the front sheet 1 and back sheet 2 by edge seams as at 6 but separate from the front sheet at the wrist edge 7, so that the front or palm structure of the glove is practically in the form 70 of a pocket to receive padding such as 8, Fig. 2. The front and lining sheets are usually provided at the wrist edges with similarly-spaced eyelets 9 so that these sheets may be secured together at the wrist by a lace 10 after the padding is adjusted or readjusted by the player.

The principal feature of my invention is a guard or combined guard and pad 15, Fig. 3, consisting of a sheet of suitable material, 80 usually rubber, of moderate but substantial thickness and cut to the general flat contour of the glove; thus it includes in the present instance a central or palm portion 16, separate finger portions 17, and a thumb portion 18, that enter and fit flatly within the tubular fingers and thumb of the glove. At the tips of the finger and thumb portions I preferably provide strap or pocket formations 19 to receive the tips of the fingers, and thus 85 facilitate insertion of the guard sheet in the glove. Perforations 20 are desirably made near the wrist edge 21, these being spaced the same as the spacing of the eyelets 9 above mentioned. Desirably, although not 90 necessarily, a socket or pocket formation 22 is formed substantially at the center of the palm portion 16, this socket consisting of a concavely pressed or molded portion of the integral guard material. 100

The guard 15 is inserted in the palm structure of the glove while the wrist edges of the front and lining sheets are unconnected, this insertion being facilitated by placing 5 the tips of the fingers and thumb in the guard formation 19. The thumb and finger portions of the guard are thus easily inserted in the similar parts of the palm structure and thereupon the guard is positioned as sufficiently shown in Figs. 1 and 2, and is secured by inserting the lace 10 through eyelets 9 and the registering holes 20 of the 10 guard.

When such a guard is used or located in 15 the glove in the manner described, the palm padding may in some cases be omitted, since the guard sheet will usually provide sufficient protective padding for the palm of the player. Finger padding 8 may, however, be retained, the finger portions of the 20 guard being located between the padding and the lining 5. If necessary the palm padding may also be retained.

The guard sheet 15 is located between the 25 palm surface of the player's hand and the front leather 1 of the glove, and being of rubber or other moisture-proof material, entirely prevents access of perspiration from the hand to the front leather, and any dis- 30 coloration or other deterioration thereof from this cause. The lining sheet 5 is interposed between the guard and the hand, so that the hand is not in contact with the rubber. The palm portion 16 of the guard 35 overlying the palm of the hand ordinarily provides sufficient hand protection from ball impact, as indicated above. The concave socket or pocket formation 22, located at a central position of the palm, where the ball 40 is naturally received, also has a substantial cushioning effect due to the more or less loosely overlying palm material 16, which tends to form an air pocket in the concavity 22; and this pocket or concave formation 45 also conforms substantially to the ball surface and assists the player, even when the glove is new, in properly receiving and retaining the ball in his gloved hand, after the fashion of the ordinary glove or mitt 50 after it has been thoroughly "broken in," as well understood by ball players.

The guard may easily be removed at any time, as, for example, to facilitate drying the glove lining material 5, by removing 55 the lace 10, and easily reinserted, as sufficiently explained above.

I claim:

1. A game glove having a palm structure including an outer sheet and a lining, and a 60 guard sheet of moisture-proof material of substantial thickness located between the outer sheet and the liner and preventing access of moisture from the hand of the user to the outer sheet, the glove palm structure including tubular thumb and finger for-

mations, and the guard sheet having substantially corresponding formations provided at their tips with means to receive the user's finger and thumb tips and facilitate insertion of the guard sheet in the glove palm 70 structure.

2. A game glove having a palm structure including an outer sheet and a lining, and a guard consisting of a single sheet of moisture-proof material located between the 75 outer sheet and the liner and preventing access of moisture from the hand of the user to the outer sheet, the guard sheet having in its wrist margin perforations to receive a lace inserted through them and registering 80 perforations in the wrist margins of the palm structure to retain the guard in position.

3. A player's glove having a palm structure including a front and a lining sheet 85 unconnected except at certain edges, and also having tubular finger and thumb formations, and a guard sheet of rubber of substantial thickness, contoured in substantial conformity to the glove palm contour and located between the front and lining sheets thereof. 90

4. A player's glove having a palm structure including a front and a lining sheet unconnected except at certain edges, and also having tubular finger and thumb formations, and a guard sheet of rubber of substantial thickness, contoured in substantial conformity to the glove palm contour and removably located between the front and 95 lining sheets thereof. 100

5. A player's glove having a palm structure including a front and a lining sheet unconnected except at certain edges, and also having tubular finger and thumb formations, and a guard sheet of rubber of substantial thickness, contoured in substantial 105 conformity to the glove palm contour and located between the front and lining sheets thereof, the guard sheet having at the tips of its finger and thumb portions, pockets to receive the user's finger tips and facilitate insertion of the guard sheet into the glove palm structure. 110

6. A player's glove having a palm structure including a front and a lining sheet unconnected except at certain edges, and also having tubular finger and thumb formations, and a guard sheet of rubber of substantial thickness, contoured in substantial 115 conformity to the glove palm contour and located between the front and lining sheet thereof, the guard sheet having at its wrist margin perforations spaced in conformity with perforations in adjacent parts of the palm front and lining sheets to receive a lace 120 and retain the guard sheet in position. 125

7. A sweat guard for player's gloves, consisting of a sheet of moisture-proof material cut in conformity to the palm outline of a glove and including finger and thumb por- 130

tions extending from a central palm portion, the finger and thumb portions having at their tips socket formations to facilitate insertion of the guard sheet into a glove palm structure.

5 8. A sweat guard for player's gloves, consisting of a sheet of moisture-proof material cut in conformity to the palm outline of a glove and including finger and thumb portions extending from a central palm portion, 10 and spaced perforations in the wrist margin to receive a lace.

In testimony whereof I affix my signature.

JOHN BROMLEY.
